UNITED STATES PATENT OFFICE.

DAVID O. MARSHALL, OF ST. LOUIS, MISSOURI, ASSIGNOR TO MOUND CITY WOOD
HEEL & MFG. CO., OF ST. LOUIS, MISSOURI, A CORPORATION OF MISSOURI.

HEEL-GROOVING MACHINE.

Application filed June 18, 1923. Serial No. 646,153.

To all whom it may concern:

Be it known that I, DAVID O. MARSHALL, a citizen of the United States, residing at St. Louis, Missouri, have invented a certain 5 new and useful Improvement in Heel-Grooving Machines, of which the following is a full, clear, and exact description, such as will enable others skilled in the art to which it appertains to make and use the 10 same.

This invention relates to a machine for forming a groove or recess in a shoe heel at the junction of the breast and bottom end face of the heel so as to improve the 15 appearance of the heel.

One object of my invention is to provide a machine of the general character referred to which is so constructed that it can be operated successfully at a high speed by an 20 unskilled workman.

Another object is to provide a machine of the character referred to that can be adjusted easily to adapt it to heels of various sizes and styles and to vary the depth and length 25 of the groove or recess formed in the heel.

Figure 1 of the drawings is an end elevational view of a machine constructed in accordance with my invention.

Figure 2 is a detail view, showing a heel 20 arranged in engagement with the cutter of the machine.

Figure 3 is a side elevational view of the machine.

Figure 4 is a top plan view of the heel 25 carrier.

Figure 5 is a top plan view of the cutter and the heel carrier, illustrating two adjustments of the carrier.

Figure 6 is a top plan view of the cutter 30 and the heel carrier, showing how the carrier can be adjusted longitudinally of the axis of the cutter to adapt the machine to a relatively high French heel; and

Figure 7 is a perspective view of a heel 35 that has been grooved by my improved machine.

Referring to the drawings which illustrate the preferred form of my invention, A designates a rotary cutter, preferably a 40 tapered cutter provided with longitudinally-disposed teeth, B designates a horizontal shaft to which said cutter is fastened, C

designates a belt for driving said shaft and D designates the frame of the machine.

The machine is equipped with a movable 55 heel carrier E which is so constructed that a heel can be placed in same and said carrier thereafter moved towards the cutter A so as to cause said cutter to form a recess or groove *w* in the heel at the junction of the breast *y* and the bottom end face *z* of the heel, as shown in Figures 2 and 7. The carrier E is so constructed that only a few seconds are required to place the heel in the carrier, move the heel into engagement with 60 the cutter and then remove the heel from the carrier. Moreover, the carrier is so constructed and arranged that no skill on the part of the operator is required in the operation of manipulating the carrier during 65 the operation of grooving the heel.

In the form of my invention herein illustrated the carrier E is oscillatingly mounted on the frame D of the machine at one side of the cutter A and is adapted to be 70 moved from the position shown in full lines in Figure 1 into the position shown in dotted lines in said figure to bring the heel into engagement with the cutter. At the completion of the grooving operation the 75 carrier is restored to the position shown in full lines in Figure 1 and the grooved heel in the carrier is removed and replaced by an ungrooved heel. The particular construction of the carrier E is immaterial, so

far as my broad idea is concerned, so long as it is of such design that the heel can be arranged in operative position in same quickly, will be held securely in the carrier during the grooving operation and can be re- 80 moved from the carrier quickly at the completion of the grooving operation.

One convenient way of constructing the carrier is to provide it with a socket piece 1 upon which the heel can be laid sidewise with its longitudinal axis extending lengthwise of the cutter A and its breast *y* presented towards said cutter, a stop 2 being arranged at the right hand side of said socket piece so as to form an abutment for the upper end face *w* of the heel and another stop 3 being arranged in front of said socket piece so as to form an abutment for the breast *y* of the heel. In most instances I form the socket 85 90 95 100

piece 1 from lead or other relatively soft metal that can be molded so as to conform approximately to the shape of one-half of the heel and mount said socket piece on the carrier in such a way that it can be removed easily and replaced by another socket piece when the style or size of the heel to be grooved in the machine is changed. In the machine herein shown the carrier E is provided with a base portion to which the socket piece 1 is firmly clamped by a bolt or other suitable fastening device 4 that passes through an open-ended slot in the socket piece, and said base portion is provided at its right hand edge with an upwardly-projecting flange that constitutes the stop 2 previously referred to.

The carrier E is preferably secured to the upper end of a rock arm F that is oscillatingly mounted on a horizontally-disposed support G which projects forwardly from the front side of the frame of the machine, and said frame is equipped with stops 5 and 6 that co-operate with the rock arm F to limit the movement of the carrier E relatively to the cutter A, the stop 6 being preferably adjustably mounted, as shown in Figure 1, so that it can be set in different positions to control the depth of the groove α formed in the heel by the cutter A.

In order that the machine may be used for grooving heels of various styles and sizes means is provided for enabling the carrier E to be adjusted angularly relatively to the cutter A, raised and lowered relatively to said cutter and also adjusted longitudinally of the axis of the cutter. In the form of my invention herein illustrated the support G on which the rock arm F is mounted is rigidly connected to a vertically-adjustable plate 7 whose lower end rests upon an adjusting screw 8 that is adapted to be manipulated so as to raise and lower the plate 7 and thus change the level of the carrier relatively to the cutter. After the plate 7 has been set in the proper position it is clamped securely to the frame D of the machine by clamping bolts 9 on said plate that pass through vertically-disposed slots in cross pieces at the front end of the frame, as shown in Figure 1. This adjustment of the carrier is used to center the heel properly with relation to the cutter, and thus cause the cutter to form a symmetrical groove or recess in the breast of the heel. In order that the shape or form of the groove α in the heel may be varied without changing the cutter A or substituting a cutter of different form, the carrier E is mounted on the rock arm F in such a way that it can be turned into the position shown in dotted lines in Figure 5, so as to arrange the heel on the carrier at an angle to the axis of the cutter. One convenient way of accomplishing this is to provide the base portion of the car-

rier with a rigid, depending rod 10 that is screwed into an internally-screw-threaded bore in the rock arm F, a lock nut 11 being provided for holding the carrier in adjusted position. In the event the vertical adjustment of the plate 7 which carries the rock arm F is not sufficient to bring the longitudinal axis of the heel in horizontal alignment with the longitudinal axis of the cutter A, the lock nut 11 can be loosened and the rod 10 on the carrier can be rotated so as to move the carrier vertically relatively to the rock arm F on which it is mounted. Thus, the rod 10 and lock nut 11 not only provide for the angular adjustment of the heel carrier, but they form a separate means for adjusting the carrier vertically, which can be used to increase the range of adjustment of the machine or used in the event it is desired to make a quick vertical adjustment of the carrier without disturbing the position of the vertically-adjustable plate 7 on the frame of the machine.

When the machine is to be used for grooving a relatively high French heel, it is necessary to adjust the carrier E longitudinally of the axis of the cutter A from the position shown in full lines in Figure 6 into the position shown in dotted lines in said figure. In the form of my invention herein illustrated this is accomplished by providing the rock arm F with an internally screw-threaded sleeve 12 whose threads co-operate with screw threads 13 on the horizontally-disposed support G to move the rock arm F longitudinally of said support when said sleeve 12 is rotated. As shown in Figure 3, the sleeve 12 is retained in adjusted position on the support G by a lock nut 14, and the rock arm F is provided at its lower end with a horizontally-disposed, tubular portion 15 that is free to oscillate on the sleeve 12.

While I have herein illustrated my invention embodied in a machine in which the portion of the machine that carries the heel is adapted to be moved relatively to the cutter to bring the heel into and out of engagement with the cutter, and is so constructed that it can be adjusted into various positions to adapt the machine to heels of different styles and sizes and to vary the shape and depth of the groove formed in the heel, I do not wish it to be understood that my broad idea is limited to a machine of this particular construction, as my invention, broadly stated, consists of a machine composed of a cutter and a heel carrier arranged in such a way that one of said elements can be moved relatively to the other to cause the cutter to form a groove or recess in the heel at the junction of the breast and bottom end face of the heel and so constructed and combined that one of said elements can be adjusted relatively to the other vertically,

angularly and in a direction lengthwise of the longitudinal axis of the cutter.

Having thus described my invention, what I claim as new and desire to secure by Letters Patent is:

1. A machine for grooving shoe heels, comprising a tapered, rotatable cutter provided with longitudinally-disposed cutting teeth, a heel carrier for holding a heel in a position extending longitudinally of the axis of the cutter with its breast presented towards the cutter and its upper end portion positioned beyond the end of the cutter, and a support on which said carrier is rockably mounted, disposed parallel to the longitudinal axis of the cutter, said carrier being adapted to be rocked towards the cutter so as to cause the cutter to form a groove in the lower end portion of the breast of the heel.

2. A machine for grooving shoe heels, comprising a tapered, rotatable cutter provided with longitudinally-disposed cutting teeth, a heel carrier for holding a heel in a position with its longitudinal axis disposed parallel to the longitudinal axis of the cutter and with its breast presented towards the cutter, a support on which said carrier is rockably mounted disposed parallel to the longitudinal axis of the cutter, said carrier being adapted to be swung towards the cutter so as to cause the cutter to form a groove in the lower end portion of the breast of the heel, and means for enabling said carrier to be adjusted relatively to said cutter so as to center the breast of the heel with respect to the longitudinal axis of the cutter.

3. A machine for grooving shoe heels, comprising a tapered, rotatable cutter provided with longitudinally-disposed cutting teeth, a movable heel carrier constructed to hold a heel in a position extending longitudinally of the axis of the cutter with its breast presented towards the cutter and its upper end portion positioned beyond the large end of said cutter, means for enabling said carrier to be rocked on an axis parallel to the longitudinal axis of the cutter so as to move the heel into and out of engagement with the cutter to cause the cutter to form a groove in the lower end portion of the breast of the heel, and means for enabling the carrier to be adjusted lengthwise of the longitudinal axis of the cutter.

4. A machine for grooving shoe heels, comprising a tapered, rotatable cutter provided with longitudinally-disposed cutting teeth, a movable heel carrier constructed to hold a heel in a position extending longitudinally of the axis of the cutter with its breast presented towards the cutter and its upper end portion positioned beyond the large end of said cutter, means for enabling said carrier to be rocked on an axis parallel to the longitudinal axis of the cutter so as to move the

heel into and out of engagement with the cutter, to cause the cutter to form a groove in the lower end portion of the breast of the heel, means for enabling the carrier to be adjusted relatively to the cutter to center the heel with respect to the cutter, and means for enabling the carrier to be adjusted lengthwise of the longitudinal axis of the cutter.

5. A machine for grooving shoe heels, comprising a rotatable cutter, a heel carrier, a removable socket piece on said carrier that conforms approximately to the outline of one-half of the heel and on which the heel is adapted to be laid sidewise with its breast presented towards the cutter, and means for supporting the carrier and permitting it to be rocked about an axis parallel to the longitudinal axis of the cutter to cause the cutter to form a groove in the lower end portion of the breast of the heel.

6. A machine for grooving shoe heels, comprising a rotatable cutter, a heel carrier oscillatingly mounted on a support arranged parallel to the longitudinal axis of the cutter and adapted to be swung towards and away from the cutter, stops on said carrier that are adapted to co-act with the breast and with the upper end face of the heel to maintain the heel in such a position that the cutter will form a groove or recess in the lower end portion of the breast of the heel when the carrier is moved towards the cutter, and a variable socket piece on said carrier on which the heel is laid sidewise with its breast presented towards the cutter.

7. A machine for grooving shoe heels, comprising a tapered, rotatable cutter provided with longitudinally-disposed cutting teeth, a rock arm arranged to swing about an axis parallel to the longitudinal axis of said cutter, a heel carrier on said rock arm provided with means for holding a heel in a position with its breast presented towards the cutter and its upper end portion positioned beyond the large end of said cutter, whereby the cutter will form a groove or recess in the lower end portion of the breast of the heel when the carrier is moved towards the cutter, means for enabling the axis of movement of said rock arm to be shifted relatively to the longitudinal axis of the cutter, and means for enabling said rock arm to be adjusted lengthwise of the longitudinal axis of the cutter.

8. A machine for grooving shoe heels, comprising a horizontally-disposed shaft provided with a rotatable cutter, a frame that carries said shaft, a horizontally-disposed support on said frame that is stationary during the operation of grooving a heel, a rock arm oscillatingly mounted on said support, a heel carrier on said rock arm provided with means for maintaining a heel in such a position that it is disposed lengthwise of the longitudinal axis of the

cutter with its breast presented towards the cutter and the upper end portion of the heel positioned beyond the end of the cutter, means for enabling said support to be raised and lowered, and means for enabling the heel carrier to be adjusted angularly with relation to the cutter.

9. A machine for grooving shoe heels, comprising a horizontally-disposed shaft 10 provided with a rotatable cutter, a frame that carries said shaft, a horizontally-disposed support on said frame that is stationary during the operation of grooving a heel, a rock arm oscillatingly mounted on 15 said support, a heel carrier on said rock arm provided with means for maintaining a heel in such a position that it is disposed lengthwise of the longitudinal axis of the cutter with its breast presented towards the

cutter and its upper end portions positioned outside of the cutting zone, means for enabling said support to be raised and lowered, and means for enabling said rock arm to be adjusted longitudinally of said support. 20 25

10. A machine for grooving shoe heels, comprising a horizontally-disposed shaft provided with a rotatable cutter, a horizontally-disposed support arranged underneath said shaft, a rock arm on said support, a heel carrier on said rock arm, means for enabling said carrier to be adjusted angularly with relation to said rock arm, means for enabling said support to be raised and lowered, and means for enabling said rock arm to be adjusted longitudinally of said support. 30 35

DAVID O. MARSHALL.
